BALL POINT PEN

Francis E. Gruber, St. Paul, Minn., assignor to
Brown & Bigelow, St. Paul, Minn.

Application December 27, 1945, Serial No. 637,327

5 Claims. (Cl. 120—42.03)

1

My invention relates to a fountain pen wherein a replaceable ink reservoir unit is slideably positioned within the casing of the pen. I provide means for automatically releasing the writing point of the pen back into the casing to conceal the writing point by the casing itself. My pen does not require an extra cap over the writing point for closing the pen.

A feature of my invention resides in forming a pocket clip for holding the pen in one's pocket, which clip is formed with a spring end adapted to release a spring trigger carried by the ink reservoir or unit and by means of a spring within the casing the entire unit is automatically moved longitudinally to conceal the writing point of the pen.

This pen is designed with a ball writing point and the ink chamber is adapted to supply a viscous non-drying ink having a controlled surface tension which ink is adapted to be carried out of the reservoir by the writing ball by the surface tension of the ink on the inner surface of the ball within the passageway of the unit leading from the ink chamber to the ball. Thus, as the ball rotates over the surface to be written on, it will draw the ink out of the ink chamber and deposit it on the surface being written on.

The ink reservoir is provided with an atmospheric opening in the rear of the same to balance the air pressure therein.

In the drawings forming part of the specification, Figure 1 is a longitudinal section view through the casing of my pen showing the writing ball withdrawn into the casing.

Figure 2 is a similar section to Figure 1 showing the writing ball projected out of the casing in writing position.

The fountain pen A is formed with an ink reservoir unit B which is slideably mounted in the casing 10 of the pen A.

The ink unit B is held by the pin 11 from rotation within the casing 10. The pin 11 is anchored to the rear end of and projects from the outer surface of the ink unit B and slides in the longitudinal slot 12 formed in the collar 13 which is anchored in the casing 10.

The writing end of the casing 10 includes the conical writing tip 14 which is threaded at 15 to the casing barrel 10. Thus the tip 14 may be removed when desired.

At the rear end of the casing 10 I provide a collar 16 which is threaded at 17 to the casing. The collar 16 may be removed so that the ink reservoir unit B may be withdrawn out of the casing 10 when desired.

5 The unit B is freely slideable longitudinally in the casing 10 and is adapted to be urged in a backward direction by the coil spring 18 which is located in the writing tip 14. The coil spring 18 acts to push the entire unit B backward into the position illustrated in Figure 1 with the annular shoulder 19 formed on the rod 20 which is anchored in the rear end of the ink unit B in any suitable manner. A head 21 projects from the rod 20 which slides through the collar 16 and into exposed position as illustrated in Figure 1 when the writing ball 22 is drawn inside the casing of the pen A as illustrated in Figure 1.

10 A spring catch 23 is held by the rod 20 to the unit B. The spring 23 is provided with a lug 24 which engages in the opening 25 formed in the casing 10. Thus the spring catch 23 with the lug 24 engaged in the opening 25 acts to hold the ink unit and writing ball 22 in writing position as illustrated in Figure 2. The writing ball 22 and the unit B are forced into writing position by pressing upon the outer end of the head 21. This causes the spring catch 23 to engage in the opening 25 with the lug 24 projecting through opening end with the spring 18 fully compressed as illustrated in Figure 2.

15 A pocket clip C is secured to the casing 10 and is formed with a spring arm 26 to the ball end 27 for holding the pen A in a person's pocket when it is not being used.

20 The clip C is formed with a spring tail end 28 having a knob 29 positioned directly over the opening 25. When the reservoir B and the writing ball 22 are in the position illustrated in Figure 2, the lug 24 is directly beneath the ball end 27.

25 When it is desired to release the writing unit B back into the casing 10 it is only necessary for the operator to press the tail end 28 of the clip C to force the lug 24 by the ball end 29 out of the opening 25, whereupon the spring 18 acts to automatically move the entire ink unit B back into the casing of the pen A, thus automatically releasing the writing tip 22 from writing position into the inoperative position illustrated in Figure 1.

30 The pen normally may be carried in the user's pocket, retained therein by the clip C and with the writing ball 22 concealed in the casing of the pen A.

35 When the pen A is desired for use the writing ball 22 may be moved into writing position by pressing upon the knob or end 21 causing the lug 24 to engage in the opening 25 and hold the ink unit B in writing position. When it is desired to replace the ink unit B with a new unit filled with 40 ink, it is only necessary to remove the collar 16

whereupon the spring 18 will push the unit B out of the rear end of the casing far enough so that the unit B may be readily engaged and removed from the casing. The casing of the pen A may also be taken apart by removing the writing end 14 from the barrel portion 10.

My clip C is designed with the spring tail end 28 to release the unit B from writing position to the inoperative position as illustrated in Figure 1 whenever it is desired.

This pen A is designed to use an ink reservoir B which is filled at the factory with a viscous ink having a controlled viscosity and wherein the capillary attraction is designed to flow toward and against the writing ball 22 until the entire casing B is empty and needs to be replaced. A pen of this character does not need to be filled very often, and the ink used therein does not require a blotter as the ink line is uniformly controlled by the size of the ball.

The operation of my pen A is simple, and the primary facts herein contained reside in an ink reservoir unit B which may be moved longitudinally in the casing automatically by pressing on the rear end of the pocket clip without affecting in any manner whatsoever the spring arm 26 which normally holds the pen A in a person's pocket. Furthermore the spring means for moving the reservoir in its entirety in a backward direction, and the spring catch 23 with the lug 24 form the primary features of this invention.

I claim:

1. A capless fountain pen having a tubular casing, a slidable ink reservoir unit positioned within the casing, spring means for moving said reservoir in a backward direction to conceal the writing point within the casing, a shoulder for controlling the backward movement of the ink unit, a pocket clip attached to said casing, a spring tail end formed on said pocket clip, and a spring catch carried by said ink unit which is adapted to be released by said spring tail of said pocket clip when the same is depressed, whereupon said spring means automatically moves said ink unit and writing tip longitudinally in said casing to conceal the writing tip when the same is not desired for use.

2. A capless fountain pen including a casing, an ink reservoir unit having a writing ball mounted on one end, a pressable knob formed on the rear end of said ink reservoir, a spring catch carried by said reservoir unit adapted to engage in a recess formed in said casing to hold said unit with the ball in writing position, a spring normally urging said reservoir unit in a backward direction out of writing position, and a pocket clip having a rear spring end for engaging said

catch to release the same when said end of said clip is depressed; whereby said ink unit and writing tip are automatically moved to conceal the writing tip within the casing when said catch is released.

3. A capless fountain pen including a replaceable ink unit having a writing ball on the forward end thereof, a casing for enclosing said ink unit, a spring catch carried by said unit for holding the same in writing position, spring means for normally urging said unit in a backward direction in said casing, and a spring arm formed on the rear end of a pocket clip adapted to release said catch and cause said spring to move said unit to a position within said casing to cover the writing ball and protect the same when not in use.

4. A fountain pen having a tubular casing open on each end, an ink reservoir unit having a writing ball on one end and a head on the other end which normally projects out of the rear end of said casing when said unit is in a position within said casing to conceal the writing end of the unit therein, a spring catch carried by said unit adapted to engage in a recess in said casing when said unit is moved by pressing against the rear end of the unit to force the same into writing position, a coil spring extending around the forward end of said unit adapted to urge said unit in a backward direction, a pocket clip having a spring pocket engaging arm end, and a spring arm extending in line with end projecting from the rear of said pocket clip adapted to form a trigger which is adapted to be pressed to release said catch, whereupon said coil spring automatically moves said unit longitudinally in said casing to conceal the writing end of said unit within said casing.

5. A capless fountain pen including a casing, a removable replaceable ink reservoir unit having a writing ball mounted in one end, a spring catch for holding said unit in writing position, a spring arm projecting from the rear of a pocket clip for releasing said catch, and a coil spring extending around the front of said unit and concealed in said casing for automatically moving said unit out of writing position to conceal the writing ball within the casing.
